UNITED STATES PATENT OFFICE.

WILLIAM ANDERSON, OF HULTON, PENNSYLVANIA.

DESIGN FOR A MANTEL.

SPECIFICATION forming part of Design No. 19,872, dated June 3, 1890.

Application filed February 20, 1890. Serial No. 341,218. Term of patent 7 years.

To all whom it may concern:

Be it known that I, WILLIAM ANDERSON, a citizen of the United States, residing at Hulton, in the county of Allegheny and State of Pennsylvania, have invented a certain new Design for Mantels A A; and I do hereby declare the following to be a full, clear, and exact description of the invention, such as will enable others skilled in the art to which it pertains to make and use the same, reference being had to the accompanying drawings, which form a part of this specification.

Figure 1 is a front elevation of a mantel showing my design. Fig. 2 is an end sectional elevation of the same, these two views being deemed necessary to fully illustrate my design.

The leading feature of my design consists in the outlines of the pilasters, the mantel-board, and frieze, when viewed in elevation, as in Fig. 1.

In the accompanying drawings I have shown the pilasters *a* extending from the hearth to the mantel-board *b* and provided with raised caps *c* at the top. These caps *c* are partly

beveled about their lower edges, as is also the central portion of the pilasters *a*. The mantel-board *b* is fluted about its upper front edges and sides and a strip of molding *d* placed beneath. This strip *d* may be divided 30 at the center and a block *e* attached. A strip *f*, placed back of the molding *d*, serves to form an even ground or surface and bring the same flush with the two upper caps *c*. A quarter-round strip *h* is formed on the lower 35 edge of this piece *f*. The base of the frieze *i* is partially beveled, which adds to its attractiveness. The grounds *k* and fire-strips *l* are of ordinary construction.

Having thus described my design, I claim— 40
The design for a mantel, as herein described and shown.

In testimony that I claim the foregoing I hereunto affix my signature this 23d day of January, A. D. 1890.

WM. ANDERSON. [L. S.]

In presence of—

M. E. HARRISON,
C. C. LEE.
